(57) **CLAIM**

We claim the ornamental design for an auxiliary antenna for a fixed antenna handset, as shown and described.

DESCRIPTION

FIG. 1 is a top view of an auxiliary antenna for a fixed antenna handset, according to this invention;

FIG. 2 is a front elevational view thereof;

FIG. 3 is a first side view thereof;

FIG. 4 is a second side view thereof;

FIG. 5 is a rear elevational view thereof; and,

FIG. 6 is a bottom view thereof.

The broken line showing of a wireless handset is for illustrative purposes only and forms no part of the claimed design.

The cord shown in FIGS. 2-4 is broken away for ease of illustration to indicate indeterminate length.
